DESIGN FOR A GOLD STAR MEMORIAL PLAQUE

Frank J. O'Connor, Dwight, Ill.

Application June 2, 1943, Serial No. 110,350

Term of patent 7 years

To all whom it may concern:

Be it known that I, Frank J. O'Connor, a citizen of the United States of America and a resident of Dwight, in the county of Livingston and State of Illinois, have invented a new, original, and ornamental Design for a Gold Star Memorial Plaque, of which the following is a specification, reference being had to the accompanying drawing, forming part thereof.

Fig. 1 is a front elevational view of a plaque showing my new design; and

Fig. 2 is a vertical central sectional view thereof on a reduced scale.

I claim:

The ornamental design for a gold star memorial plaque, as shown.

FRANK J. O'CONNOR.
